UNITED STATES PATENT OFFICE

BENJAMIN G. CAMPBELL AND CHARLES C. WING, OF OAKLAND, CALIFORNIA

BOTTLE CLOSURE

Application filed December 9, 1929. Serial No. 412,712.

This invention relates to bottle closures and method of applying same, providing for retaining of a protecting means or cap over the mouth of the bottle and the like, and is an improvement on the copending application of the applicant, Benjamin G. Campbell, Serial No. 184,590, filed April 18, 1927.

The invention is described herein with relation to milk bottles since that is the relation 10 in which it has been used by applicants, but it is to be understood that it is not limited to that use, and is adaptable to closing cylindrical cartons, sacks, bags and receptacles generally, especially the method of securing 15 the ends of a flexible member about the open end of a receptacle.

It has been found desirable to place over the mouths of milk and similar bottles, to protect the pouring edge thereof, a suitable cap 20 covering retained in position by holding means, which latter is removed by the housewife when it is desired to lift the cap or cover from the bottle mouth and pour the contents 25 from the bottle. The holding means now employed are objectionable, as in many instances they are made of metal which may cut or scratch the hands when opening the bottle, and in most instances they require a tool or prying implement to release the same and often remain on the neck of the bottle when 30 it is washed by the housewife and returned to the distributor for refilling. The failure to completely remove the holding means from the bottle necessitates the dairyman, distributor, or filling station, as the case may be, 35 maintaining an attendant or operator for this purpose, and entails considerable expense, both in labor and in loss of time. Many 40 municipalities require a top closure for milk bottles which extends over the entire top, as distinguished from the common disk which is inserted in the bottle mouth and frictionally held therein.

In the related copending application above referred to, a fracturable seal is employed to maintain the binding means in position, but it takes time for such a sealing means to set, which means expense, and which, if it adheres 45 to the skirt of the cap, distorts the form of the

cap skirt so that the skirt does not firmly fit the neck of the bottle when replaced.

The present invention has for its principal object to provide a receptacle closure and a method of applying same, adaptable to very 55 rapid mechanical application, which, when in position, will securely hold the cap in position over the bottle mouth, and which is capable of ready removal by the housewife without the necessity of tools or implements, and 60 which does not distort the skirt of the cap, and when released from the bottle cap, is also severed from the bottle. Another object is to provide a means of the above type which is adaptable for ready disposal by the housewife, is extremely inexpensive in its application 65 and use, and which does not delay the filling of the bottles, and is also efficient for the purpose intended.

The invention consists broadly in tightly 70 wrapping or winding a flexible element, either elastic or non-elastic, a plurality of times about the skirt of a bottle cap to hold the same in position on the bottle mouth, and securing the position of the ends of the element 75 by interengaging the element upon itself, or by other means not adhering to said element, nor to the skirt of the cap, and thereby prevent the releasing of the wrappings, and leaving an end portion of the flexible element so 80 disposed as to afford a grip being had thereon, whereby the flexible element may be readily disengaged from its wound position circumferential of the skirt of the cap.

With the above mentioned and other objects in view, the invention consists in the novel construction and combination of parts hereinafter described, illustrated in the accompanying drawings, and set forth in the claim hereto appended, it being understood 85 that various changes in the form, proportion, size and minor details of construction, within the scope of the claim, may be resorted to without departing from the spirit 90 or sacrificing any of the advantages of the 95 invention.

Referring to the drawings forming part of the present application:

Fig. 1 is a view in elevation of the preferred embodiment of the invention as ap- 100

plied to the skirt of a sealing cap for the conventional type of milk bottle.

Fig. 2 is a view of a portion of the flexible element at the point of interengagement of its ends, with ends looped.

Figs. 3, 4 and 5 are views of several modifications of a portion of the flexible element, showing means of securing the ends thereof.

Referring to the drawings, wherein like characters of reference designate corresponding parts, 1 indicates the neck of a conventional milk bottle, over the mouth and the upper pouring edge of which is positioned a closure cap 2 of any of the conventional types, having a skirt 3 preferably pleated or crimped, as at 4, enabling the same to be tightly drawn into contact with the outer surface of the bottle neck 5.

A flexible member, preferably a string 6, is wrapped or wound tightly under tension a plurality of times around the skirt 3, and the ends where they extend beyond each other are securely positioned by the engagement thereof by flexible means associated therewith in such manner that each of the end portions of the string 6 are normally releasably held against disengagement, responsive to frictional contact of the flexible windings with the cap skirt.

This is accomplished preferably by applying the primary end 7 of the flexible string in angular relation to the circumferential windings around the cap skirt so that the circumferential windings will lap over the primary string end, and after the desired plurality of windings have been made circumferentially of the cap skirt, inserting the secondary end 8 of the string between the plurality of circumferential windings and the cap skirt, or the circumferential windings may be first completed, and the respective ends thereafter inserted under the plural windings encircling the cap, as best shown in Fig. 2. Variations may be adapted in the manner of positioning the string ends, such as shown in Fig. 3, wherein the ends of the string are twisted upon each other, and in Figs. 4 and 5, wherein a separate flexible member is employed to position the string ends.

It is a well known fact that a plurality of windings of a rope, cord, wire or the like, around a cylindrical, prismatic or other body, absorbs in the coils around said body and in the frictional pressure against said body, the stress of tension against said cord or rope, and this principle is herein applied to practically eliminate the stress which would otherwise be present against the fastening of the string if a single winding were made circumferentially of the cap skirt.

With the cap in the position as in the drawings, and the member 6 retaining the same in position against the bottle neck 5, the binding member 6 may be readily and easily re-

leased from its tightly wound position so as to release the cap skirt by manipulating the secondary end 8 of the binding means 6, so that the cord member is freed from intertwining with the other wraps, and removing from said cap skirt the windings thereon. Or, as shown in Fig. 2, either end 7 or 8 may be likewise released by manually pulling same.

Having thus described our invention, we claim:

In combination with a receptacle whose neck is externally enlarged at the mouth thereof forming a bead, a skirted cap placed over the mouth of the receptacle with the skirt portion depending therefrom about the bottle neck, a continuous flexible cord circumferentially wound about the skirt portion a plurality of times and having a portion adjacent each its ends frictionally and releasably engaged between a plurality of wraps of said flexible cord and the outer wall of the receptacle, each of said end portions having a portion free of said windings whereby either of the respective end portions may be released from said engagement by direct pull thereon.

In testimony whereof we have signed our names to this specification.
